CLAIM

The ornamental design for an ultrasound transducer probe holder, as shown and described.

DESCRIPTION

FIG. 1 is a top-front-left perspective view of an ultrasound transducer probe holder showing my new design; FIG. 2 is a bottom-front-left perspective view thereof; FIG. 3 is a top-rear-right perspective view thereof; FIG. 4 is a bottom-rear-right perspective view thereof; FIG. 5 is a front elevational view thereof; FIG. 6 is a rear elevational view thereof; FIG. 7 is a top plan view thereof; FIG. 8 is a bottom plan view thereof; FIG. 9 is a right elevational view thereof; FIG. 10 is a left elevational view thereof; and, FIG. 11 is a top-rear-right perspective view thereof, wherein the ultrasound transducer probe holder is shown with an ultrasound transducer probe. The broken lines showing an ultrasound transducer probe in FIG. 11 are included for the purpose of illustrating environmental structure and form no part of the claimed design.
